(57) **CLAIM**

I claim the ornamental design for a wrecking tool, as shown and described.

DESCRIPTION

FIG. 1 is a top, front perspective view of the wrecking tool according to my new design;

FIG. 2 is a bottom, rear perspective view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a front elevation view thereof; and,

FIG. 8 is a rear elevation view thereof.

The broken lines are included for the purpose of illustrating the unclaimed portions of the wrecking tool and form no part of the claim.
